UNITED STATES PATENT OFFICE.

JAMES C. SCOTT, OF PORTSMOUTH, OHIO, ASSIGNOR TO THE SCOTT KNITTING COMPANY,
OF PORTSMOUTH, OHIO.

UNION UNDERGARMENT.

No. 904,022.

Specification of Letters Patent. Patented Nov. 17, 1908.

Application filed June 13, 1908. Serial No. 438,370.

To all whom it may concern:

Be it known that I, JAMES C. SCOTT, a citizen of the United States, residing at Portsmouth, in the county of Scioto and State of 5 Ohio, have invented a new and useful Union Undergarment, of which the following is a specification.

This invention has relation to union undergarments and it consists in the novel construction and arrangement of its parts as 10 hereinafter shown and described.

The object of the invention is to provide a garment of the character indicated having an opening extending from the neck down 15 the front and under the crotch and along the lower portion of the posterior.

A gusset is attached to one side of that portion of the opening which extends into the posterior and said gusset is projected 20 down into the leg of the garment upon the same side. A flap is attached to the opposite side of the posterior portion of the opening of the garment and also extends down into the leg at the same side of the garment. 25 The gusset and flap are coequal in length and are joined together at their upper ends at a point at the middle of the back of the garment. The gusset is triangular in shape while the flap is in the form of a polyhedron 30 and has one side attached to the back of the garment and extending transversely with relation to the same. The flap is provided with a free upper end portion which is adapted to overlap the upper end of the gusset 35 and the portion of the garment adjacent thereto. Securing devices are mounted upon the garment adjacent the gusset and to these devices the free end portion of the said flap may be attached. The gusset and flap are 40 so mounted upon the garment that they lie in close contact with each other when the wearer is in standing position or in seated position and the free end portion of the flap is engaged with one of the securing devices.

45 When, however, the wearer is in seated position and the free end portion of the flap is disengaged from the securing device the gusset and flap have a tendency to gap with relation to each other whereby sufficient 50 opening is provided for the posterior of the wearer. The gusset and flap also coöperate with each other in strengthening the opposite side portions of the garment at the pos-

terior portion of the opening therein and as said parts extend down into the legs of the 55 garment the legs are supported upon the intermediate portion of the garment at points between the upper and lower extremities of the said legs. The securing devices for the free end portion of the flap are located substantially in alinement with the hip joint of 60 the wearer. The said flap when in engagement with the securing devices will not bind or interfere with the free movement of the body of the wearer when assuming a seated 65 or standing posture. This is due to the fact that the point of attachment of the free end portion of the said flap is substantially at the center upon which the leg swings with relation to the body of the wearer. 70

In the accompanying drawings: Figure 1 is a rear perspective view of the garment as it would appear upon one in standing posture and showing the free end portion of the flap in engagement with one of the securing 75 devices. Fig. 2 is a rear view of the lower portion of the garment showing the same as it would appear upon one in standing posture with the free end portions of the flap disengaged from the securing devices. Fig. 80 3 is a front view of the garment showing the same as it would appear upon one in standing posture. Fig. 4 is a perspective view of the lower portion of the garment showing the same as it would appear upon one in 85 sitting posture and with the free end portion of the flap disengaged from the securing devices. Fig. 5 is a view showing the pattern of the flap, and Fig. 6 is a view showing the pattern of the gusset. 90

As has been above stated the garment is in the form of a union suit of under-wear and is provided with the front opening 1 which passes down under the crotch and extends into the posterior opening 2. The gusset 3 95 is triangular in shape and its side representing the hypotenuse of the triangle is attached to one of the sides of the opening 2 in the posterior of the garment. The shortest side of the said gusset 3 extends down into the 100 leg of the garment upon the same side thereof as that to which the said gusset is attached. The button or buttons 4 are located upon the gusset 3 in the vicinity of the angle 105 thereof formed between the long and short sides of the triangle described by the said

2
gusset. The flap 5 is inserted at its lower end into the other leg of the garment in a similar manner as that described for the lower portion of the gusset 3. The flap 5 is 5 in the form of a polyhedron and the angle at its lower end is equal to the angle at the lower end of the gusset 3. The longest side of the flap 5 is equal in length to the longest side of the gusset 3. The longest side of the 10 flap 5 is sewed to the side of the opening 2 in the posterior of the garment in a similar manner as has been described for the side representing the hypotenuse of the triangle described by the gusset 3. The upper portion of the flap 5 is provided with an area 6 which forms a flap and is adapted to lie over the upper portion of the gusset 3 and which is adapted to be attached to securing devices mounted upon the garment proper. The upper 15 end of the gusset 3 is attached to the upper end of the flap 5 at the upper end of the longest side thereof. The flap 5 is provided with a short side 7 which is attached to the back of the garment and which extends 20 transversely with relation to the same. The upper end of the longest side of the flap 5 is attached to the middle of the back of the garment, consequently, the short side 7 of the said flap is disposed at one side of the 25 middle of the garment. The flap 5 is provided at a point opposite the angle formed between the long and short side of the gusset 3 with a button hole 8 which is adapted to receive the button 4 mounted upon the said 30 gusset. The upper portion of the flap 5 is provided with a strip 9 which is adapted to be turned over along the line 10, as shown in Fig. 5, and which constitutes a reinforcing strip for the upper or free portion of the 35 said flap 5. The area 6 of the flap 5 is provided with a button hole 11 and the edges of the flap 5 along the area 6 converge toward each other toward the point where the button hole 11 is situated. The buttons 12 are 40 attached to the garment and are mounted upon the strip 13 sewed against the inner side of the garment. The said button hole 11 is adapted to receive any one of the buttons 12 which constitute securing devices for 45 holding the free end portion of the flap 5 snugly against the upper portion of the gusset 7 and the rear portion of the garment. The said buttons 12 are located substantially 50 opposite the hip joint of the wearer, consequently, the area 6 of the flap 5 will not bind or interfere with the movement of the wearer in assuming a seated or standing position.

From the above description it is obvious that a union suit of underwear is provided 55 having the opening, as specified, which opening is reinforced at its posterior portion by means of the gusset and the flap which extend into the leg portion of the garment and effectually brace and support the same. It 60 will also be seen that when the free end por-

tion of the flap 5 is secured by means of the buttons 12 that the said free end portion of the said flap will lie snugly against the upper portion of the gusset 3 and the rear portion of the garment and effectually close 70 the posterior opening therein. When, however, the free end portion of the flap 5 is disengaged from one of the buttons 12 and the wearer assumes a seated position the gusset 3 and the said flap 5 will have a tendency to gape with relation to each other whereby ample opening is provided. It will also be seen that by providing a series of buttons 12 located as specified that should the said flap 5 shrink or expand such shrinkage or expansion may be compensated for 75 without discomfort to the wearer. Also by reason of the fact that the said flap 5 extends down into one of the legs of the garment at one end and is secured at its upper end to the upper end of the gusset 3 which at its lower end extends down into the opposite leg of the garment when the free end portion of the said flap 5 is adjusted upon the buttons 12 such adjustment affects both legs 80 85 90 95 of the garment.

While the foregoing description relates to union suits, the parts described may be used on drawers alone and are especially adapted for ladies' wear.

Having described my invention, what I claim as new and desire to secure by Letters-Patent is:

1. A garment having a continuous front, crotch and posterior opening, a gusset attached to one side of the posterior portion of said opening and extending into one of the legs of the garment a flap attached to the opposite side of the posterior portion of the opening in the garment and extending into the other leg of the garment, said flap and gusset being coequal in length and being connected together at their upper ends, said flap having an upper edge which is attached to the back of the garment and lies in a line at one side of the middle thereof, said flap having a free end portion adapted to lie over the upper portion of the gusset and the adjacent rear portion of the garment and securing devices for the free end portion of the flap located substantially in alignment with the hip joint of the wearer.

2. A garment having a continuous front, crotch and posterior opening, a gusset attached to one side of the posterior portion of said opening, and extending into one of the legs of the garment, a flap attached to the opposite side of the posterior portion of the opening in the garment and extending into the other leg of the garment, said flap and gusset being connected together at their upper ends, said flap having an upper edge which is attached to the back of the garment and lies in a line at one side of the middle thereof, said flap having a free end

portion adapted to lie over the upper portion of the gusset and the adjacent rear portion of the garment, and means for adjustably securing the free end portion of the flap substantially in alinement with the hip joint of the wearer.

In testimony that I claim the foregoing

as my own, I have hereto affixed my signature in the presence of two witnesses.

JAMES C. SCOTT.
